(57) **CLAIM**

The ornamental design of a connector for a lid securing device, as shown and described.

DESCRIPTION

FIG. 1 is a perspective view of a connector for a lid securing device according to the new design and showing the environment;

FIG. 2 is a perspective view of the connector for a lid securing device of FIG. 1;

FIG. 3 is a left side view of the connector for a lid securing device of FIG. 1;

FIG. 4 is a front elevation view of the connector for a lid securing device of FIG. 1;

FIG. 5 is a left side view of the connector for a lid securing device of FIG. 1;

FIG. 6 is a rear elevation view of the connector for a lid securing device of FIG. 1;

FIG. 7 is a top plan view of the connector for a lid securing device of FIG. 1; and,

FIG. 8 is a bottom plan view of the connector for a lid securing device of FIG. 1.

The broken lines in the drawings depict portions of the connector for a lid securing device that form no part of the claimed design.
